Primary Examiner — Karen S Acker**CLAIM**

I claim the ornamental design for a scientific world flag based on the tree of life, as shown and described.

DESCRIPTION

FIG. 1 is the front horizontal elevation view of the scientific world flag based on the tree of life;

FIG. 2 is the top edge view thereof; and,

FIG. 3 is the rear horizontal elevation view thereof.

1 Claim, 2 Drawing Sheets**FIG. 1**

FIG. 2

FIG. 3
